[57] CLAIM

The ornamental design for a holder for candles, as shown and described.

DESCRIPTION

FIG. 1 is a perspective view of a holder for candles showing our new design;

FIG. 2 is a left side view thereof, the right side view being identical;

FIG. 3 is a front view thereof, the rear view being identical;

FIG. 4 is a top view thereof;

FIG. 5 is a bottom view thereof;

FIG. 6 is a perspective view of a second embodiment of a holder for candles showing our new design;

FIG. 7 is a front view thereof, the right side, left side, and rear views being identical thereto;

FIG. 8 is a top view thereof; and,

FIG. 9 is a bottom view thereof.
